CLAIM

The ornamental design for a flexible bag filling support, as shown and described.

DESCRIPTION

FIG. 1 is a perspective view of a flexible bag filling support showing my new design;

FIG. 2 is a perspective view thereof, shown inserted into a flexible bag;

FIG. 3 is a top plan view thereof;

FIG. 4 is a bottom plan view thereof;

FIG. 5 is a front elevational view thereof, the rear view being a mirror image; and,

FIG. 6 is a left side elevational view thereof, the opposite side being a mirror image.

The broken line illustration shows environmental structure and forms no part of the claimed invention.
